his Atty.

UNITED STATES PATENT OFFICE.

RICHARD MACKIN, OF BOSTON, MASSACHUSETTS.

WRENCH.

Application filed April 6, 1922. Serial No. 550,204.

To all whom it may concern:

Be it known that I, RICHARD MACKIN, a citizen of the United States of America, and a resident of Boston, in the county of 5 Suffolk and Commonwealth of Massachusetts, and whose post-office address is 61 Orchard Field St., Dorchester, have invented certain new and useful Improvements in Wrenches, of which the following is a specification.

This invention relates to wrenches, particularly to the type known as monkey wrench and while shown in connection therewith it is obvious that it may be used 15 with equally good results in certain types of pipe wrenches or certain forms of pipe cutting tools.

An object of the invention is to produce a wrench that may be rapidly adjusted to a 20 nut, bolt or other object to be operated upon, with a minimum of manipulation and time in so doing.

A further object of the invention is to so construct the wrench that but one hand is 25 required to make a rapid initial adjustment, and the finer final adjustment of it to the object upon which it is intended to operate.

A still further object of the invention is to 30 simplify and make more compact certain portions of the wrench pertaining to the means for disengaging the adjusting nut from the threaded or toothed angular member or movable jaw.

The present invention is an improvement 35 on patent granted to me February 25, 1919, No. 1,295,546, wherein the adjusting nut is held in engagement with the toothed angular member by a spring referred to as "an arched shape tail", pressure upon which caused the adjustment nut to move out of engagement with said member.

When said disengagement took place and the wrench was to be adjusted for use, the 40 angular member was pushed toward the stationary jaw and thereafter the pressure on said tail was released and the adjusting nut again engaged the toothed member.

This operation required the use of two 45 hands and considerably more time than is required in the present invention, and furthermore the arched tail was at times in the way and susceptible to breakage and detracted from the appearance of the wrench 55 in general.

To the attainment of the above objects the

invention consists in certain novel features of construction, arrangement and combination of parts which will be fully understood from a description of the drawings and the 60 claim hereinafter given.

Of the drawings:

Figure 1 represents in elevation, partially broken away, one form of wrench to which the invention is applicable.

Figure 2 a view similar to Figure 1 certain of the parts being in section but showing the adjusting nut disengaged from the toothed portion of the movable jaw and the position said jaw would assume relative 70 to a nut or bolt when said disengagement took place.

Figure 3 a section on the line 3—3 Figure 1.

Figure 4 a section on the line 4—4 Figure 75 1.

Figure 5 a plan view of the nut carrying plate detached.

Like characters designate like parts throughout the several figures of the drawings.

Referring to the drawings:

The wrench shown herewith is of the monkey wrench type and consists of a handle 10 of such arrangement as to receive the 85 shank 11 of a stationary jaw 12, said shank having a shoulder 13 abutting the top of handle 10 and a threaded portion 14 to receive the nut 15, and if desired said handle and shank may be held together by means 90 of rivets 16.

A movable jaw 17 adapted to slide on said shank relatively to said jaw 12 has an extension 18 adapted to be received and housed in said handle 10, a spring 19 also in said handle tends to press said extension and attached movable jaw 17 toward the jaw 12.

The said extension 18 is provided with a thread-like teeth 20 on one face thereof adapted to be normally engaged by an adjusting nut 21, rotary movement of which in one direction or the other causes said jaw 17 to travel toward or away from the jaw 12.

The nut 21 is pivotally mounted on a 105 plate 25 which is arranged to slide transversely of the shank 11 but is normally held in the position Figure 1 by means of the spring 26, said plate having an upstanding portion 27 against which said spring 110 abuts, and which conveniently acts as a thumb or finger piece upon which to press

when it is desired to slide said plate and disengage said nut from the screw 20. The plate 25 has an opening therein as at 28 through which the shank 11 passes and by 5 which it is guided in its sliding movements.

The said opening is of sufficient length to permit of the proper amount of movement of said plate to disengage said nut.

The plate 25 is held from movement longitudinally of the shank 11 in one direction by the top of the handle 10 against which it bears and by the shoulders 30 formed on the shank 11 in the other direction, between which and the top of said handle 10 said plate is free to move transversely of said shank. As seen in Figure 1 the wrench is about to be applied to a nut or bolt, the stationary jaw 12 being already in engagement therewith. By the use of 20 one hand the operator may press the spring abutment 27 thereby sliding plate 25 against the action of spring 26 whereupon the nut 21 will disengage from the teeth 20 and immediately the spring 19 will force the extension 18 and attached jaw 17 upwardly till said jaw meets the nut or bolt as seen in Figure 2. The pressure may now be released and the nut 21 will resume engagement with the teeth 20, and if necessary or 30 desired the jaw 17 may be further adjusted toward or from the said bolt by the nut in one direction or the other.

If for any reason the jaws should clamp the bolt so tightly that the wrench could 35 not be readily removed therefrom without disengaging the nut 21, the operator may press the abutment 27 to disengage the nut and at the same time force the handle 10 toward the bolt, which action will separate 40 the jaws and of course compress the spring 19, and at this time the pressure may be again released and the nut engaged with the teeth 20 and the wrench is ready for another operation.

From the foregoing it will be readily seen 45 that the wrench is readily operated by the use of one hand, this feature being of especial importance in certain classes of work, such for instance as automobile repair work where a wrench of this character 50 may oftentimes be used on bolts or nuts that are so inaccessible that the ordinary wrench requiring the use of two hands to adjust would be useless.

It is not known that a wrench of this 55 class having a movable jaw that is normally held locked relatively to the stationary jaw but automatically moved toward said jaw upon being unlocked has ever been used, and therefore it is not the intention to limit 60 this invention to the precise construction herein shown and described, as it is obvious that various changes may be made therein without departing from its spirit and scope.

Having described the invention I claim: 65

In a wrench of the class described, a stationary jaw having a shank; a handle to which said jaw shank is secured; a movable jaw adapted to slide on said shank having a threaded extension adapted to enter a recess 70 in said handle; an adjusting nut normally in engagement with said threaded extension and normally operable to regulate the opening between said jaws; a slidable plate on which said nut is revolvably mounted and having 75 an end upwardly turned at approximately right angles thereto to form an abutment for a spring; said jaw shank having a shoulder adapted to slidably retain said plate in operative position; and a coiled 80 spring interposed between said abutment and said shank whereby said nut is normally held in engagement with said threaded extension.

Signed by me at Boston, Mass, this 29th 85 day of March, 1922.

RICHARD MACKIN.
